UNITED STATES PATENT OFFICE

2,655,184

CURRENT-SUPPLY MEANS FOR WEFT
STOP MOTIONS

Paul Depoilly, Flixecourt, France, assignor to
Société dite: Saint Frères, Société Anonyme,
Paris, France

Application February 19, 1952, Serial No. 272,460
In France February 21, 1951

4 Claims. (Cl. 139—371)

1

Weaving looms and notably circular looms are frequently equipped with electric weft stop motions which are mounted on the shuttles and which partake of their circular movement. The shuttles are enclosed between the two thread sheets and the reed, and current is supplied on the one hand through the reed and on the other hand through one of the thread sheets with the interposition of machine parts between the fixed machine elements of the loom and the shuttle, which considerably strains the threads and results in an early wear of the parts in contact therewith.

The present invention has for its object means to supply current to electric weft stop motions carried by weaving loom shuttles and notably by circular loom shuttles in which the inconveniences inherent to prior devices are avoided; with this end in view, the current is led in and out through the reed, of which a number of elements are connected to the one pole of the current source while the others are connected to the other pole.

Two embodiments of the present invention are shown by way of example in the appended drawings.

Figure 1 is a diagrammatical plan view of the first embodiment.

Figure 2 is a cross sectional view taken on line II—II in Fig. 1.

Figure 3 is a fractional front view of the reed.

Figure 4 is a plan view of a second embodiment.

Figure 5 is a sectional view taken on line V—V in Fig. 4.

The circular weaving loom illustrated in Figs. 1 and 4 comprises a shuttle 1 which carries a weft stop motion 2 which partakes of its circular motion. Current is led to and out of said motion through leads 3 and 4 ending in brushes 5, 6 which slidably engage the dents of the reed.

In the embodiment illustrated in Figs. 1 to 3, the dents, instead of being continuous between their conductive supports 7 and 8, are radially offset; the two resilient contacts 5, 6 are vertically offset in such a manner that the one will only engage the dents 9 while the other will only engage the dents 10; the conductive support 7 which carries the dents 9 is connected to the one pole while the other conductive support 8 which carries the dents 10 is connected to the opposite pole.

2

In the embodiment illustrated in Figs. 4 and 5 the dents 11 occupy the whole space comprised between their insulating supports 12 and 13; all the teeth belonging to sectors *a* are connected to the one pole while those which belong to sector *b* are connected to the opposite pole and those which belong to the narrow sectors *c* separating the sectors *a* and *b* are insulated.

10 The size of said sectors is such that whenever the brush 5 is in engagement with any one of the dents in either sector *a* or sector *b* the brush 6 will be in engagement with some dent in sectors *b* or *a* respectively.

15 It will be appreciated that in this arrangement the current is led to the weft stop motion without resorting to any mechanism that may damage the threads in the warp or the weft, and this, with a few movable contacts as possible and consequently with maximum safety.

20 It is to be understood that the two aforescribed embodiments of the invention are only given for the purpose of exemplification and by no means of limitation and that many modifications may be made therein without thereby departing from the scope of the invention.

What I claim is:

1. In a circular loom including a shuttle, a reed slidably engaged by said shuttle and an electric weft stop motion carried by said shuttle, a number of the reed dents being connected to the one pole of the weft stop motion electric source and another number of said reed dents being connected to the opposite pole of said source, a pair of resilient brushes partaking of the rotation of the shuttle, connected each to one of the terminals of the weft stop motion and arranged to remain in frictional engagement respectively with the dents connected to the one and the other poles of the electric source.

2. An arrangement according to claim 1 wherein in each dent is divided into two sections offset relative to one another, the one of which is connected to the one pole and the other to the other pole, the pair of resilient brushes being likewise offset relative to one another and co-operating each with those dent portions which are connected to one and the same pole of the electric source.

3. An arrangement according to claim 1 wherein in each dent is divided into two sections which are offset radially relative to one another and lo-

cated at unequal levels, those dents which belong to the one kind being conductively connected to the one pole of the electric source and those which belong to the other kind being connected to the other pole, the pair of resilient brushes being likewise offset radially relative to one another and located at unequal levels in order that they may co-operate each with the dents of the related kind.

4. An arrangement according to claim 1 where- 10
in the dents are grouped in equal sectors of a

circle each of which is connected to one of the poles of the electric source.

PAUL DEPOILLY.
